UNITED STATES PATENT OFFICE.

CLIFTON CORLEY, OF GREENVILLE, SOUTH CAROLINA.

MOTOR-SUPPORT FOR SPINNING-MACHINES.

1,364,076.

Specification of Letters Patent.

Patented Jan. 4, 1921.

Application filed May 25, 1920. Serial No. 384,116.

To all whom it may concern:

Be it known that I, CLIFTON CORLEY, of Greenville, in the county of Greenville and State of South Carolina, have invented certain new and useful Improvements in Motor-Supports for Spinning-Machines, of which improvement the following is a specification.

This invention relates to the supports for the driving motors of spinning or twisting machines, or the like, and has for its objects to provide an improved support to strengthen the machine, to eliminate vibration, to save valuable floor space, and to provide a simple, compact construction of neat appearance.

Motors for driving these machines have heretofore been mounted on brackets extending out from the face of the front frame of the machine, and connected by gearing with the driving shaft of said machine, but this arrangement has been found to produce excessive vibration which wears out the gearing and drive chains, and is also objectionable in the operation of the machines. This prior arrangement also takes up considerable floor space at the front end of the machine, and obstructs the space in the aisle between the rows of said machines in the cotton mill.

According to my improvement, the motor is supported on a hanger bracket or cradle, which is suspended from, and rigidly secured to, the ring rails of the spinning machine inside of the end frame, there being a driving connection from the motor shaft to the main shaft of the machine.

In the accompanying drawing: Figure 1 is an elevation of the front end of a spinning machine, with my improvement applied thereto; and, Fig. 2, a side elevation of the same.

A portion of an ordinary form of spinning machine is shown in the drawing, comprising a front end frame, 5, having upright posts supported on the floor of the mill, and longitudinal rails, called ring rails, 6, bolted at their ends to the end frame, 5, and extending to the corresponding end frame at the other end of the machine, (not shown), for carrying the various spindles, reels, etc., (also not shown), all of which may be of the usual well known construction. According to the usual practice in cotton mills, these spinning machines are arranged in rows, with an aisle located between the adjoining

front end frames of the respective rows, and the machines may be driven by individual electric motors.

An outwardly projecting bracket, 7, is rigidly attached at its ends to the two posts of the end frame, 5, and carries the outer bearing, 8, of the main shaft, 9, of the spinning machine, on which shaft is mounted the driving gear or sprocket wheel, 10.

According to my improvement, the electric motor, 11, for driving the machine is supported on a cradle or hanging bracket, 12, formed of an integral casting having a horizontal bed portion for the motor and upwardly extending webs at either side adapted to be rigidly bolted to the ring rails, 6, of the spinning machine inside of the end frame, 5. The cradle thus not only serves as a hanger for supporting the motor beneath the machine, but also acts as a rigid brace for strengthening the ring rails of the spinning machine, and greatly reduces the vibration. The motor shaft is provided with a sprocket gear, 13, which is connected by a drive chain, 14, with the sprocket gear, 10, on the main shaft of the machine.

My improvement also has the advantage of saving valuable floor space, as the motor is out of the way beneath the spinning machine, and obstruction to the passage way through the aisle is thereby avoided. It also adds to the useful life of the drive chain, as it prevents vibration, which causes a cutting out of the chain.

Having now described my invention, what I claim as new and desire to secure by Letters Patent is:

1. In a spinning machine, the combination with the end frame, ring rails and main shaft, of a hanger bracket rigidly secured and suspended from the ring rails, a motor mounted on said bracket, and a driving connection therefrom to the shaft of said machine.

2. In a spinning machine, the combination with the end frame, ring rails and main shaft, of a hanger bracket rigidly secured and suspended from the ring rails, inside of the end frame, a motor mounted on said bracket and having a shaft extending out beyond the end frame, gears mounted on said shafts outside of the end frame, and a driving connection for said gears.

3. In a spinning machine, the combination with the end frame, ring rails and main shaft, of a hanger bracket rigidly secured

and suspended from the ring rails, a motor mounted on said bracket and having a shaft, gears mounted on said shafts, and a drive chain connecting said gears.

- 5 4. In a spinning machine, the combination with the end frame and ring rails, of a hanger bracket formed of an integral cast-

ing having a horizontal bed for a motor, and upwardly extending webs at both sides rigidly fastened to the ring rails inside of 10 the end frame.

In testimony whereof I have hereunto set my hand.

CLIFTON CORLEY.
